(57) **CLAIM**

The ornamental design for a writing instrument clip, as shown and described.

DESCRIPTION

FIG. 1 is a perspective view showing a writing instrument clip embodying our new design;

FIG. 2 is an enlarged perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The indicia in FIG. 2 and the structural features in FIGS. 1 through 6 depicted by means of broken lines have been shown for illustrative purposes only and form no part of the claimed design.
